STEERING WHEEL RIM

Robert T. Mora, 1186 Emerson Ave.,
Campbell, Calif. 95008

Filed July 10, 1970, Ser. No. 24,240

Term of patent 14 years

Int. Cl. D12—16

U.S. Cl. D14—30

FIG. 1

FIG. 2

FIG. 3

FIG. 1 is a front elevational view of a steering wheel rim showing my new design;

FIG. 2 is a side elevational view of the steering wheel rim shown in FIG. 1; and,

FIG. 3 is a sectional view taken on the plane designated by line 3—3 in FIG. 1.

The elements shown in broken lines are included for illustrative purposes only.

I claim:

The ornamental design for a steering wheel rim, as shown and described.
